UNITED STATES PATENT OFFICE.

OLIVER B. GOLDING, OF ELWOOD, INDIANA.

HOT-MILL FURNACE.

1,138,555.

Specification of Letters Patent.

Patented May 4, 1915.

Application filed June 30, 1914. Serial No. 848,267.

To all whom it may concern:

Be it known that I, OLIVER B. GOLDING, a citizen of the United States, residing at Elwood, in the county of Madison and State 5 of Indiana, have invented new and useful Improvements in Hot-Mill Furnaces, of which the following is a specification.

This invention relates to improvements in hot mill furnaces such as are used in making 10 tin plate, and more especially with reference to improvements in the construction of the bottom or floor of such a furnace, the object of the invention being to effect improvements in the construction of the furnace bottom to prevent the formation of 15 scale and the accumulation of dirt on the furnace bottom and to also increase the efficiency of the furnace bottom in its effect in heating the steel bars and to avoid the necessity of cleaning the furnace bottom at 20 short periods of time, another object being to increase the durability as well as the efficiency of the furnace bottom.

With the above and other objects in view 25 the invention consists in the construction, combination and arrangement of devices hereinafter described and claimed.

In the accompanying drawings:—Figure 1 is a vertical sectional view of a hot mill 30 furnace provided with a bottom or floor constructed in accordance with my invention. Fig. 2 is a horizontal sectional view of the same. Fig. 3 is a transverse sectional view of the same. Fig. 4 is a detail elevation of 35 one of the cast iron bricks arranged and used in the construction of the furnace bottom. Fig. 5 is a plan of the same. Fig. 6 is a detail horizontal sectional view of the rear portion of the furnace.

The furnace 1 is provided with the usual 40 fire box 2, grate 3, ash pit 4, heating chamber 5 and bridge wall 6. The charging door is indicated at 7 and the smoke stack at 8.

My improvements relate more especially 45 to the construction of the bottom of the furnace or that portion thereof which forms the floor of the heating chamber 5. The floor line of the furnace is indicated at 9 and in accordance with my invention I provide a 50 series of spaced walls 10 on the floor 9 which walls may be constructed of fire brick or other suitable material and in practice are four and one half inches wide, four and one half inches high and are spaced four 55 and one half inches apart. These dimensions may however be varied without de-

parting from the spirit of my invention. The walls 10 are here shown as arranged transversely of the floor and below the heating chamber 5 but may be otherwise arranged without departing from the spirit of my invention. The floor 9 is provided with a longitudinal clean-out channel 11 which extends from the ash pit to the rear wall and communicates with the spaces between 60 the walls 10, through vertical openings 12. The walls 10 are constructed with openings 13 which extend through them and immediately above the floor 9 to permit heat to circulate below the bottom of the furnace heating chamber 5 and to equalize the heat at 65 all points in the bottom of the chamber.

The bottom 14 of the heating chamber 5 is, in accordance with my invention, constructed of alternately arranged fire brick 75 15 and cast iron bricks 16, the fire brick being placed flatwise and the cast iron bricks being placed edgewise so that the upper portions of the cast iron bricks extend through 80 and above the upper surfaces of the intermediate fire brick, as clearly shown in Figs. 1 and 3. On opposite sides of the cast iron bricks 16 are lugs 17 which enter the spaces between the ends of the fire brick and serve 85 to hold the latter in place. The cast iron bricks are provided at their upper side edges with notches 18 and each cast iron brick has a longitudinal bore 19 and is provided at one end with a projecting nipple 20 to enter 90 the bore of the next adjacent brick so that a continuous bore or passage is formed through each series of cast iron bricks, from end to end of the floor. The bridge wall 6 is provided with a bore 21 which extends therethrough and is provided with openings 95 22 which communicate with the bores or channels 19 and is also provided with vertical bores 23 which extend from the bore or channel 21 to the upper side of the bridge wall. The rear wall of the furnace also has a bore 24 with which the bores 19 communicate as at 25. Hence when the furnace is 100 in operation air is drawn in through the bore 25, passes through the bores 19 of the series of cast iron bricks and passes through the bores 21 and 23 in the bridge wall up 105 into the furnace. The air which is thus caused to pass through the fire bricks serves to prevent them from becoming unduly heated. The air also by being heated during its passage through the cast iron bricks 110 is discharged into and combines with the

gases of combustion as they pass from the fire box 2 over the bridge wall and into the heating chamber 5 and thus serves to greatly promote combustion, effect an economy in 5 the use of fuel and increase the heating efficiency of the furnace.

The cast iron bricks present raised surfaces above the fire brick 15 on which the bars rest while being heated, serve thus to 10 space the bars above the fire brick bottom 15 so as to permit the free circulation of heat under said bars so that the heating efficiency of the furnace is greatly increased. Moreover by thus spacing the bars above the 15 fire brick bottom scaling is prevented or very greatly reduced and moreover the bars are kept clean while being heated. The cast iron bricks are extremely durable and hence require renewing only at long periods of 20 time. The dirt is prevented from accumulating on the bottom and passes from the spaces between the walls 10 through the openings 12 into the clean-out channel 11 and may be readily removed from time to

time from such channel as will be understood. Hence my improved construction of the furnace bottom obviates the necessity of cleaning the same weekly or at short periods of time as heretofore has been necessary in furnaces of this type constructed in 30 the usual way.

Having thus described my invention, I claim:—

In a furnace of the class described a bottom comprising a floor having a longitudinal clean-out channel and vertical openings communicating therewith, spaced walls on the said floor and on opposite sides of said vertical openings, fire bricks on said spaced walls and cast iron bricks also on said spaced walls and arranged alternately with and extending above the fire bricks.

In testimony whereof I affix my signature in presence of two witnesses.

OLIVER B. GOLDING.
